(57) **CLAIM**

The ornamental design for temples for spectacles, as shown and described.

DESCRIPTION

FIG. 1 is a perspective view of a first embodiment of temples for spectacles, showing my new design;

FIG. 2 is a front view thereof;

FIG. 3 is a left side view thereof;

FIG. 4 is a top plan view thereof;

FIG. 5 is a bottom plan view thereof;

FIG. 6 is a rear view thereof;

FIG. 7 is a perspective view of a second embodiment of temples for spectacles, according to the invention;

FIG. 8 is a front view thereof;

FIG. 9 is a left side view thereof;

FIG. 10 is a top plan view thereof;

FIG. 11 is a bottom plan view thereof;

FIG. 12 is a rear view thereof;

FIG. 13 is an "internal" left side view thereof;

FIG. 14 is a perspective view of a third embodiment of temples for spectacles, according to the invention;

FIG. 15 is a front view thereof;

FIG. 16 is a left side view thereof;

FIG. 17 is a top plan view thereof;

FIG. 18 is a bottom plan view thereof;

FIG. 19 is a rear view thereof;

FIG. 20 is a perspective view of a fourth embodiment of temples for spectacles, according to the invention;

FIG. 21 is a front view thereof;

FIG. 22 is a left side view thereof;

FIG. 23 is a top plan view thereof;

FIG. 24 is a bottom plan view thereof; and,

FIG. 25 is a rear view thereof.

The material shown in broken lines is for illustrative purposes only and forms no part of the claimed design.

1 Claim, 10 Drawing Sheets
